(57) CLAIM

The ornamental design for a clip holder, as shown and described.

DESCRIPTION

FIG. 1: is a perspective view of a clip holder showing our new design;

FIG. 2: is a front view thereof;

FIG. 3: is a rear view thereof;

FIG. 4: is a top view thereof;

FIG. 5: is a bottom view thereof; and,

FIG. 6: is a right side view thereof; the left side view being a mirror image of the right side view.

The broken lines shown in FIG. 5 are included for the purposes of illustrating environment and form no part of the claimed design.
